UNITED STATES PATENT OFFICE.

ORA P. GORDON, OF HOPKINS STATION, MICHIGAN.

DEVICE FOR SECURING BARREL-HEADS IN PLACE.

SPECIFICATION forming part of Letters Patent No. 529,725, dated November 27, 1894.

Application filed May 28, 1894. Serial No. 512,737. (No model.)

To all whom it may concern.

Be it known that I, ORA P. GORDON, a citizen of the United States, residing at Hopkins Station, in the county of Allegan and State 5 of Michigan, have invented a new and useful Device for Securing Barrel-Heads in Place, of which the following is a specification.

The invention is specifically related to an improvement in that class of barrel-head se- 10 curers which are adapted to removably hold the head in place, and to be capable of adjustment to any position along the vertical extent of the barrel.

The object of this invention is to provide 15 a device which will be capable of easier manipulation than other devices of its class; one in which the securing spurs will always be in easy reach of the operator.

A further object is to so construct the de- 20 vice that it will be capable of adjustment to various sized barrels, and without the expenditure of much time and labor. These ends I attain by certain peculiar features of construction and combination and arrangement 25 of parts as will be more fully described hereinafter and finally embodied in the claims.

In the drawings: Figure 1 represents a perspective view of the upper portion of a barrel to which my invention is shown as applied; 30 Fig. 2, a horizontal section taken just above the spur-rods and looking downwardly thereon; Fig. 3, a side elevation; Fig. 4, an enlarged detail, in perspective, of one of the spur-rods.

The reference numeral 1 indicates the barrel, which may, of course, be of any construction, and 2 the top or head. The top or head is smaller than the interior diameter of the barrel, so that it may have free movement 35 therein, and has the securing device mounted on its upper side. Rigidly secured to the center of the head 2, by means of the feet 3, is the standard or post 4, through the upper end of which the pin 5 extends. The pin 5 40 is rigidly secured in place and projects out on either side of the standard, rigid metallic washers or gaskets 6 being arranged on them and at each side of the standard.

Mounted on the pin 5, one on each side of 45 the standard 4, are the levers 7, which are kept in engagement with the washers 6 and

in place by means of the nuts 8, operating on the ends of the pins and bearing loosely against the levers. The levers 7 are formed of flat sections of metal provided at their 55 upper ends with the rods 9, which terminate at their upper ends in the rings 10, whereby the levers may be operated. Each of the rods 9 bends toward the other, so that their upper ends will be longitudinally aligned and 60 so that the rings 10 will be similarly located. Below the pin 5 the levers 7 extend downwardly to the head 2, and are provided at their lower ends with an opening in which the inwardly-bent inner ends of the rods 11 65 are located so as to form a pivotal connection. The rods 11 are two in number, one for each lever 7, and project out laterally in opposite directions for a distance about equal to one-half the radius of the head 2. Formed 70 at their outer ends and extending inwardly therefrom are the trunnions or studs 12, which have the heads 13 secured to their ends and are adapted to furnish a means for connecting the rods 11 to the spur-rods. 75

14 indicates the spur-rods, and these are two in number, one for each lever 7, and ar- 80 ranged in the guides 15 and 16, so as to be capable of reciprocal movement in their seat- 85 ings. The guides 15 and 16 are one for each rod 14, and the former consists of a base- plate secured to the head 2 and having the eye 17 arising vertically therefrom, which eye embraces the rod, while the guides 16 each consist of an outwardly and downwardly 90 extending rod secured to the base of the stand- ard 4, and operating to retain the inner ends of the rods 14. The rods 14 are rectangular in cross-section and have the notches 18 formed in their upper faces. These notches may be 95 of any reasonable number, say from one to five, with two as the preferred number, and are arranged equidistant from each other and in the same relative positions on their respective rods. By the means of these 100 notches the studs or trunnions 12 are pivot- ally connected to the spur-rods, and, owing to the number of the notches and their vary- ing distances from the outer ends of the rods, the rods 11 may be connected thereto at va- rious points, so as to adjust the stroke of the rods 14. Thus, by placing the trunnions 12

in the notch which is nearest the outer end of the rods 14, the rods will be moved out as far as possible, and the device thereby adapted to a large sized barrel. On the other hand, 5 by placing the trunnions inward from the outer ends of the rods, they will not stroke so far out, and are therefore adapted to a smaller barrel.

Rigidly secured to or formed integral with 10 the outer ends of the rods 14, are the spurs or prongs 19, which are preferably two in number, and shaped as a two-tined fork. These spurs are adapted to engage the inner side of the barrel, and by such engagement 15 to bind therewith.

Secured to the standard or post 4, one on each side thereof and at opposite edges, are the studs or stops 20, which are horizontally aligned with the pin 5, and are adapted to 20 hold the levers 7 from excessive movement to the right, while movement in the opposite direction is prevented by the engagement of the spurs 19 and guide 15.

By reference to the drawings, the use and 25 principle of my invention will be apparent. When it is desired to secure the head 2 in any position throughout the vertical extent of the barrel, the head is adjusted to the desired position and the levers 7 swung so that their 30 lower ends will move outwardly. This will throw the rods 11 and consequently the rods 14 outwardly and cause the spurs 19 to engage the inner side of the barrel, thereby binding with such sides and causing the head to be 35 securely fixed in place.

It will be noticed that inward movement of the rods 14, by pressure applied longitudinally thereto, is quite impossible, since a "dead center" will exist between the trunnions 12, the upper ends of rods 11 and the 40 pins 5; or, in other words, they will be longitudinally aligned. To release the head, the upper ends of the levers are moved toward

each other, which will draw the rods 14 inwardly and allow the head to arise. 45

Having described my invention, what I claim is—

1. The combination with a head or cover arranged therein, of a post or standard secured to the head or cover, spur rods slidably mounted on the head or cover and arranged to engage a barrel at opposite sides thereof, the oppositely disposed levers arranged at an inclination and crossing each other and fulcrumed on the post or standard, and the link rods connecting the levers with the spur rods and pivotally attached to both parts, substantially as described.

2. The combination with a head or cover, of a standard rising centrally therefrom, spur rods slidably mounted on the head or cover and provided with notches, the oppositely disposed levers crossing each other and fulcrumed on the standard, and the link rods pivotally attached to the lower ends of the 65 levers and detachably engaging the notches of the spur rods, substantially as described.

3. The combination with a head or cover, of a post rising therefrom, spur rods slidably mounted on the head or cover, the oppositely disposed inclined levers fulcrumed on the post, the link rods extending from the lower ends of the levers to the spur rods and pivotally connected to them, and stops arranged on the post and limiting the swing of the 75 levers and adapted to hold the latter and the link rods in alignment to form straight braces for locking the spur rods, substantially as described.

In testimony that I claim the foregoing as 80 my own I have hereto affixed my signature in the presence of two witnesses.

ORA P. GORDON.
